UNITED STATES PATENT OFFICE

OSCAR U. ZERK, OF CLEVELAND, OHIO

BRUSH

Application filed September 8, 1931. Serial No. 561,545.

This invention relates to brushes and more particularly to brushes used for cleaning purposes in connection with cleaning liquids and under conditions where the bristles of the brush may spatter the cleaning liquid.

Typical of such uses of brushes is the use for cleaning the fingers and finger nails for toilet purposes, and with soapy water.

I therefore have illustrated and described my invention herein as applied to finger and finger nail brushes.

As is well known, the vigorous use of a finger nail brush spatters the soapy water undesirably and not only deposits it around the basin or upon the mirror adjacent the basin rendering them messy and unsightly, but unless exceedingly great care is exercised will spatter upon the clothing of the user entailing otherwise unnecessary cleaning expense.

Heretofore, nail brushes have been proposed provided with guides of various types for directing the application of the brush bristles to the extreme ends of the fingers or under the nails, but these have been inconvenient to use and decidedly limited in their application, and have had little or no effect in restraining or stopping the spattering of the bristles.

In my present invention, I employ preferably an elongated brush which may be relatively moved reciprocatorily over the finger nails or other parts of the body to be cleaned, and, generally at the ends of the brush, I have provided splash shields or spatter shields to catch the soapy water which spatters from the bristles in use. And in order to permit the brush to be moved a free, relatively long stroke, or to permit the fingers or hand to be so moved on the brush, I have arranged the shields so that they will yield when the hand or fingers come in contact with them at the end of the stroke in either direction.

Furthermore, I have found that a yielding or substantially hinging shield if yield-

ing or rotating on a relatively short radius, its retractive movement after being displaced by the hand at the end of the stroke, will tend to discharge the soapy water collected thereon and effect itself a splashing or spattering thereof, but I have found that this may be completely obviated by mounting the splash shields in such a manner that they may move on relatively large hinging or bending radii and so that their resistance to moving will be least at the beginning of their yielding movement, and by the use of relatively strong retractive springs for the shields; this prevents overthrow and consequent throwing of the soapy water collected on the inner surfaces of the shield, but on the contrary prevents loss of contact between the shields and the hand of the user on outward movements of the shields.

While in some aspects my invention contemplates employment of spatter shields entirely encompassing the brush bristles, I have found that the spatter may be effectively baffled by shields disposed only at the ends of the brush inasmuch as substantially all of the spatter takes place in the direction of movement of the brush or of the hand on the brush reciprocatorily in use.

In order to extend the use of the brush of my invention I prefer to provide spatter shields which may be moved to a spatter-baffling position at the ends of the brush and which may also be moved out of that position and into a non-functioning position when the brush is to be used for brushing relatively flat smooth surfaces, or in conditions where the spatter may be harmless.

In this connection, in the preferred form of my invention, the shield may be rotated or rocked to a recumbent position on the back of the brush.

Furthermore, I prefer to employ a spring or other resilient mechanism by which the shields may be moved with a snap movement from the spatter-baffling position to the re-

cumbent position on the back of the brush, and vice versa.

To render the brush pleasing and attractive in appearance, I prefer to seat the brush proper in a housing made from metal which may be polished and to hinge the spatter-baffling shields thereupon and to enclose the operating mechanism in the housing by a completely invisible construction.

It is therefore one of the objects of my invention to provide a brush provided at its opposite ends with spatter-baffling means.

Another object of my invention is to provide an elongated brush adapted to be reciprocated in use longitudinally or upon which the fingers may be reciprocated and provided with spatter-baffling means at the opposite longitudinal ends of the brush.

Another object is to provide a brush construction comprising a brush proper seated in a housing of highly polished metal provided with hinged spatter shields at the opposite ends thereof which may be moved with a snap-action from spatter-baffling position to a recumbent position on the back of the housing by means of a resilient mechanism within the housing.

Another object is to provide a brush of the class referred to having longitudinally oppositely disposed spatter-baffling shields and in which the shields will yield resiliently upon contact therewith of the fingers or hands of the operator.

Another object is to provide, for brushes of the class described, a quickly detachable housing-like cover provided with hinged spatter-baffling shields.

Another object is to provide a brush of the class referred to having spatter-baffling shields at the opposite ends thereof adapted to yield upon contact therewith of the hand or other part of the body being cleaned, and constructed to effect a relatively slow retractive movement after such yielding displacement.

Another object is to provide a brush of the class referred to seated in a cup-like casing whereby a chamber may be provided in the closed end or bottom of the casing and sealed water-tight at its juncture with the brush and whereby buoyancy sufficient to float the brush and the casing may be obtained.

Other objects will be apparent to those skilled in the art to which my invention appertains.

My invention is fully disclosed in the following description taken in connection with the accompanying drawings, in which:

Fig. 1 is a side elevational view of a brush embodying my invention, with spatter-shields which I may employ disposed in one operative position;

Fig. 2 is a view of the brush of Fig. 1 with the spatter-shields in another operative position;

Fig. 3 is a longitudinal cross-sectional view of the brush of Figs. 1 and 2 with one spatter-shield thereof in one position and another in another position;

Fig. 4 is an end elevational view of the embodiment of Fig. 2;

Fig. 5 is a cross-sectional view taken approximately from the plane 5 of Fig. 3;

Fig. 6 is a sectional view taken from the plane 6 of Fig. 3 with parts back of the section plane omitted for simplicity;

Fig. 7 is a view taken from the plane 7 of Fig. 1;

Fig. 8 is a view taken from the plane 8 of Fig. 2;

Fig. 9 is a view taken from the plane 9 of Fig. 2;

Fig. 10 is a view taken from the plane 10 of Fig. 2, the view being sectional and with parts omitted for simplicity;

Fig. 11 is a fragmentary view of a part shown in Fig. 3;

Figs. 12 and 13 are, respectively, side perspective and end perspective views of the embodiment of my invention of the preceding figures illustrating a mode of operation thereof;

Fig. 14 is a view similar to Fig. 2 but showing a modification;

Fig. 15 is a view taken from the top plane of Fig. 14.

Referring now to the different figures of drawing in all of which like parts are designated by like reference characters, and referring first to the first embodiment of my invention illustrated in Figs. 1 to 9 inclusive, I provide a brush having a back 2 and bristles 3, the latter being arranged in small bunches, each projecting in parallel relation from a face of the back, and held in spaced recesses 4 which are interspersed over the face of the said back. Each bunch of bristles is held in place in its particular recess by wires or threads 5 or in any other suitable manner, well known in this ancient art. The bristles are all preferably trimmed as illustrated to provide a substantially plane brushing surface 3'.

The back 2, in the embodiment of my invention illustrated, is of rectangular elongated form having a rear face 6 and a brushing operative face 7, said bristles projecting from the latter face 7.

The above relates to the elements of a hand or nail brush of the common type previously in use and to further improve such a brush I apply instrumentalities whose description follows.

Over the back 2 I apply a sheet metal casing 9 which is in the form of a cup of preferably substantially rectangular outline whose side walls are inwardly deflected to provide longitudinally extending shallow grooves 10 adapted for engagement by the operating head of the user so as to afford a firm grasp

upon the brush between the fingers and thumb while in use, in the manner best shown in Figs. 12 and 13.

The peripheral shape and size of the brush back 2 is so made that it will fit into the cup-shaped casing 9, and is firmly secured in the casing by a plurality such as four screws 11—11 projected through suitable bores in the four corners of the brush back 2 and threaded into nuts 12—12 in the corners of the casing 9. The nuts 12 are preferably dome type with one end of the thread thereof closed, and are preferably soldered into position in the casing, and the screws 11 are preferably provided with countersunk heads flush with the face 7 of the brush back.

The long sides of the brush back are chamfered or formed as shown at 13 to conform to and fit the grooves 10 whereby, when the screws 11 are drawn up tight, the brush back 2 is not only stopped upon the walls of the groove 10 to accurately position it in the casing 9, but the back 2 also makes a water-tight joint with the groove walls to prevent the entrance of water into the cup-shaped casing 9 when the brush is in use. The ends of the brush back 2, as for example at 14, Fig. 3, preferably fit tightly in the corresponding end walls 15 of the casing; and if desired, rubber packing of any suitable design may be disposed between the back 2 and the inner wall or walls of the casing 9 to further render the juncture of the back and the wall water-tight.

Thus not only may water be kept out of the casing 9 in the closed portion thereof not occupied by the brush back, but the casing being thereby rendered a closed chamber, will give buoyancy to the brush causing it to float in water with the well known attendant advantages.

In a manner to be more fully described, the casing has hinged thereto a pair of splash shields 16—16, adapted to take up two operative positions. The shields 16 extend transversely across the opposite ends of the brush and extend below or beyond the end of the bristles 3' and are transversely of greater dimension than the transverse extent of the bristle surface 3'. When the shields 16 are in this position, Figs. 1, 12 and 13, they serve to stop the spattering water, water and soap suds and the like, which may be used on the brush when it is employed to clean the fingers and nails, which operation is illustrated in Figs. 12 and 13.

In this position, the shields 16 are maintained resiliently toward the adjacent end of the brush and will yield when engaged by the fingers or hand being cleaned, one of the shields being illustrated in a yielding position in Fig. 12.

When the brush is being used for cleaning parts or surfaces to be cleaned and under conditions where it is either unnecessary or un-

desirable to stop the spattering from the bristles, the shields 16 may be rotated around upon the back of the casing 9 to the position illustrated in Figs. 2 and 8, and resiliently maintained in that position. It is also an advantage that the shields 16 may be moved to the position of Fig. 2 when the brush is not in use and when it is being transported as in a traveling bag.

The mechanism, construction and manner of assembling the elements by which the above described functions of the shields 16 may be effected will now be described.

Substantially on the center line of the casing 9 and at opposite ends thereof, are provided a pair of hinge chambers 18—18 extending transversely over only a portion of the end of the casing and projecting outwardly diagonally therefrom. The chambers 18 communicate with the interior of the cup-like casing 9. The shields 16, which preferably are alike, are formed from sheet metal, are generally rectilinear in form with rounded corners, and are generally planular with a wire 19 rolled into the peripheral edge of the shields. At one end of the shield it is cut away as at 20, Fig. 8, to clear or embrace the adjacent portions of the hinged chambers 18 when the shield is in the position illustrated in Figs. 8 and 2, and when rotating to the position of Fig. 1, and the peripheral wire of the shield extends into the cut-away portion 20 as at 21 and 22, these portions of the wire serving as trunnion hinge elements; and the hinge chambers 18 are provided with axially aligned sleeve portions 23—23 into which the hinge elements 21 and 22 are telescopically disposed and in which they rotate as in sleeve bearings.

The trunnion hinge element 22 extends farther into the chamber 18 than the trunnion element 21 and has secured on the end thereof a crank head 24 provided with an eccentrically disposed pin 25 terminating in a retaining head 26.

Both of the shields 16 are thus hingedly mounted by means of the trunnions 21 and 22 in sleeve bearings in the opposite walls of the hinge chambers 18, and by means of this bearing construction may be rotated from the position of Fig. 2 to that of Fig. 1, and vice versa. A helical spring 28 is disposed in the casing 9 between the face 6 of the brush and the bottom wall of the cup-like housing, and extends longitudinally therethrough throughout the length of the housing and at its opposite ends has hook portions 29—29 hooked over the eccentrically disposed pins 25—25 of the heads 24—24.

The pins 25 are disposed substantially in a plane with the hinge elements 21 and 22 and with the shields 16, and between these hinge elements and the main body portions of the shields 16 so that the spring 28 will resiliently maintain the shields 16, when in

the position of Fig. 1, against movement away from the ends of the brush, and when the shields are rotated to the position of Fig. 2, will resiliently maintain them flat upon the back of the housing 9. In Fig. 3, one of the shields 16 is illustrated in the position of Fig. 1 and the other in the position of Fig. 2; and in these positions the action of the spring 28 upon the eccentrically disposed pins 25 is clearly illustrated.

As hereinbefore stated, the hinge chambers 18 may be associated with the casing 9 in a water-tight manner, but if desired, perforations 30—30 may be provided in the walls of the chambers 18, whereby water which may find its way into the housing 9 may be drained out, or may be blown out by blowing into one of perforations, the water finding an exit through the other perforation.

The form of the several parts hereinbefore described may be variously modified, and the assembling of the several parts may be carried out accordingly. However, I prefer to proceed in the assembly of the several parts as follows.

The hinge chambers 18 are preferably press-formed from sheet metal and the sleeve bearing 23 thereof completely formed therein. The chambers are then projected outwardly from within the casing 9 to the positions illustrated, through suitably provided perforations in the end walls 15 and bottom portion of the cup-like casing 9, and at the periphery of the perforation soldered to make a neat and water-tight joint. The material of the casing 9 and chambers 18 is preferably one which will admit of polishing treatment and these parts when thus far assembled may, at this stage, be polished.

The wires 19 which are later to be rolled into the peripheral edges of the shields 16 are now resiliently sprung apart at the bearing ends to dispose the hinge elements 21 and 22 thereof in the bearing sleeves 23 of the chambers 18, with the element 22 extending farther into the chamber than the element 21. The shield 16 is then laid upon the wire 19 and by means of a machine operation is rolled or cyclated over the wire to completely enclose the wire in the peripheral edge of the shield.

The crank pin supporting heads 24 are then placed in the chambers 18 and secured upon the ends of the trunnion hinge elements 22—22, care being had to dispose the pins 25 in alignment with the plane of the shields 16. The heads 24 to secure them to the hinge elements 22, may be soldered thereto at this time.

The spring 28 is then hooked over the pins 25 and thereafter the brush back 2 is inserted into the casing 9 and secured therein by the screws 11.

It will be observed that the brush, as well

as the spring 28, may be renewed at any time by removal of the screws 11.

Preferably I provide the walls of the chambers 18 with extensions 35 extending inwardly along the bottom of the casing 9, these extensions being curved convexly longitudinally of the casing and concavely transversely thereof to provide a suitable guide of relatively large radius upon which the spring 28 may rest or slide to render its movement free in the operation of the shields, and to direct the hook ends of the spring upward diagonally into the chambers 18.

In Figs. 14 and 15 I have shown a modification in which the length of the brush is relatively short as may be desired when the brush is to be carried in a small toilet bag or shaving outfit, or when it is to be manufactured especially for ladies' use.

As will be observed, there is a minimum length for the shields 16 which will effectively stop the spattering of soapy water in the use of the brush as illustrated in Fig. 12; and the brush of the above described form is preferably made of sufficient length that the two shields may lie in a plane on the back of the casing as illustrated in Fig. 2. When a short brush is employed, shields 40—40 of substantially the same length as the shields 16 are employed, but are, when the shields 16 are disposed on the back of the brush, arranged to lie in juxtaposition thereupon. To this end, the bearings in one of the bearing chambers such as the chamber 41, Fig. 14, are disposed more distant from the casing 43 than the bearings in the chamber 42, thus permitting the two shields 40—40 to lie flat one upon the other.

In both of the embodiments of my invention described above, I have provided outwardly extending projections 37 and 38 at the ends of the respective casings 9 and 43 respectively, said projections forming stops for the splash shields when rotated to their operating positions. These stops maintain said shields in planes normal to the plane of the brush back.

As a further feature of improvement for the embodiment illustrated in Figs. 8 to 15 inclusive, and which will be readily understood to be also applicable to the first described embodiment of my invention, I provide a preferably sheet metal cover 36, whose end walls are provided with recesses, or as shown openings adapted to fit over the projections 38 to retain the cover in position over the brush bristles.

Preferably the cover 36 will be given a highly polished metallic or other desirable ornamental appearance suitable to the appearance of the casing 43 and the parts carried thereby including the shields.

Having thus described my invention in certain embodiments, I am aware that numerous and extensive departures may be made

from the embodiments herein illustrated and described, but without departing from the spirit of my invention.

I claim:

1. A brush comprising a back, bristles, a pair of wings hinged to the back, and resilient yieldable means to either maintain the wings in a position overlapping and extending beyond the free ends of the bristles, or in a position above the bristle free ends. 10
2. A brush comprising a back and bristles and a pair of wings hinged to the back and hingingly movable from a mid position to a position overlapping and extending beyond the free ends of the bristles or to a position above the bristle free ends, and resilient means reacting upon a wing to move it to either position when correspondingly displaced from the mid position. 15
3. A brush comprising a back and bristles and a pair of wings hinged to the back and hingingly movable from a mid position to a position overlapping and extending beyond the free ends of the bristles, or to a position above the bristle free ends, and a single resilient means reacting upon both wings to move them to either position when correspondingly displaced from the mid position. 20
4. A brush comprising a back and bristles and a pair of wings hinged to the back, cranks associated with the hinged part of the wings and resilient yieldable means associated with the cranks to either maintain the wings in a position overlapping and extending beyond the bristle free ends or in a position above the bristle free ends and on the back of the brush. 25
5. A brush comprising a back and bristles and a pair of wings hinged to the back, cranks associated with the hinged part of the wings and yieldable means associated with the cranks to either maintain the wings in a position overlapping and extending beyond the bristle free ends, or in a stopped position 30 above the bristle free ends, and stop means for stopping the wings in their last said position. 45
6. In combination, a brush comprising a back and bristles, a metal casing covering the back and a pair of spatter shields hinged to the casing, said shields adapted to overlie said back when in one position, and means concealed in said casing to maintain said shields in generally parallel positions extending in directions generally normal to the back with the shields overlapping and extending beyond the bristles when in an alternative position. 50
7. In combination, a brush comprising a back and bristles, a metal casing substantially covering the back and a pair of spatter shields hinged to the casing, resilient means concealed in said casing and adapted to maintain the shields in spatter shielding position 55
- overlapping and extending beyond the ends of the bristles. 8. In combination, a brush comprising a back and bristles, a metal casing covering the back and a pair of spatter shields hinged to the casing, mechanism concealed in the casing including resilient means reacting upon the shields and resiliently maintaining them in spatter shielding position extending beyond the ends of the bristles. 70
9. In combination, a brush comprising a back and bristles, a cup-like metal casing covering the back, a pair of spatter shields hinged to the casing, hingingly movable from a spatter intercepting position at substantially oppositely disposed end portions of the brush overlapping and extending beyond the ends of the bristles through a mid position to a position on the casing back above the bristles, and resilient means concealed in the casing reacting on a shield to move it to one said position or the other when correspondingly displaced from said mid position. 80
10. In combination, a brush comprising a back and bristles, a cup-like metal casing covering the back, a pair of spatter shields hinged to the casing, hingingly movable from a spatter intercepting position at substantially oppositely disposed end portions of the brush overlapping and extending beyond the bristle free ends through a mid position to a position above the bristle free ends, and resilient means concealed in the casing reacting on a shield to move it to one said position or the other when correspondingly displaced from said mid position. 90
11. In combination, a brush comprising a back and bristles, a cup-like metal casing covering the back, a pair of spatter shields hinged to the casing hingedly movable from a spatter intercepting position at substantially oppositely disposed end portions of the brush overlapping and extending beyond the bristle free ends through a mid position to a position above the bristle free ends, and resilient means comprising a single spring reacting on both shields to move them to one said position or the other when correspondingly displaced from said mid position. 105
12. A bristle brush comprising a back portion and a pair of spatter shields pivotally mounted on the back portion and pivotally movable from a position in which they overlap and extend beyond the free ends of the bristles to a recumbent position substantially in a common plane on the back portion. 110
13. A bristle brush comprising a back portion and a pair of spatter shields pivotally mounted on the back portion at spaced points thereon and pivotally movable from a position in which they overlap and their free ends extend beyond the free ends of the bristles to a recumbent position substantially in a common plane on the back portion, and the length of the shields being such that when in 120
- 130

recumbent position their free ends are in confronting relation.

14. A bristle brush comprising a back portion and a pair of spatter shields pivotally mounted on the back portion at spaced points thereon and pivotally movable from a position in which they overlap and their free ends extend beyond the free ends of the bristles to a recumbent position on the back portion and the length of the shields being such that when in recumbent position their free ends overlap each other.

15. In combination, a brush comprising a back and bristles and a polished metal cover covering the back, and polished metal spatter shields pivoted at substantially oppositely disposed portions of the cover and extending beyond and overlapping the ends of the bristles, and pivotally removable from the bristle overlapping position, and means to hold them in removed position.

16. In combination, a brush comprising a back and bristles, a cup-like metal casing sealably engaging the back, the cup bottom being spaced from the back to provide a buoyance chamber, a pair of spatter shields pivoted to substantially oppositely disposed end portions of the casing overlapping and extending beyond the ends of the bristles.

17. In combination, a brush comprising a back and bristles, a metal cover on the back comprising substantially oppositely disposed spaced cover portions, a pair of metal spatter shields hinged to the cover, overlapping and extending beyond the free ends of the bristles, and resilient means for maintaining the shields against substantially opposite stop portions of the cover when in said overlapping position.

18. In combination, a brush comprising a back and bristles, a metal cover on the back comprising substantially oppositely disposed spaced cover portions, a pair of metal spatter shields hinged to the said portions, overlapping and extending beyond the free ends of the bristles, and resilient means for maintaining the shields against substantially oppositely disposed stop portions of the cover when in said overlapping position, the stop portions being disposed between the free ends of the shields and their hinging connection with the cover portions.

19. As an article of manufacture, a cup-like metal housing adapted to receive the back of a bristle brush, a pair of wings hinged to spaced substantially oppositely disposed portions of the housing, resilient means secured to the wings to constrain the wings toward each other in position to overlap and extend beyond the ends of bristles on the brush back.

20. As an article of manufacture, a cup-like metal housing adapted to receive the back of a bristle brush, a pair of wings hinged to spaced substantially oppositely disposed portions of the housing, resilient means secured

to the wings to constrain the wings toward each other in position to overlap and extend beyond the ends of bristles on the brush back, the resilient mechanism being disposed in the housing.

In testimony whereof I hereunto affix my signature this 5 day of September, 1931.

OSCAR U. ZERK.
